Inventor:

Thomas Shaw

United States Patent Office.

THOMAS SHAW, OF PHILADELPHIA, PENNSYLVANIA.

Letters Patent No. 64,716, dated May 14, 1867.

IMPROVEMENT IN STEAM WHISTLES.

The Schedule referred to in these Letters Patent and making part of the same.

TO ALL WHOM IT MAY CONCERN:

Be it known that I, THOMAS SHAW, of the city and county of Philadelphia, Pennsylvania, have invented a new and improved mode of constructing Whistles; and I hereby declare the following to be a full, clear, and exact description of the same, reference being had to the accompanying drawings, and to the letters of reference marked thereon.

My invention consists in the employment of hollow tubes in the manner and for the purpose as hereafter described, and is particularly applicable to gauge-cocks, as an attachment to indicate the passage of water or steam by sound.

In order to enable others to use and practise my invention, I will proceed to describe its construction and operation. On reference to the accompanying drawing, which forms a part of the specification—

Figure 2 represents an exterior view of the whistle; and

Figure 1 a longitudinal vertical section through the centre of the same, of which *a* is a plane tube provided with a screw-thread at one end, *b*, and closed entirely or partially at the other end *c*, and is also provided with a partition, *d*, apertures *e* and *f*, all for the purpose as hereafter described. Said tube *a* is covered for a part of its length with tube *g*, which is secured to tube *a* at *h* by solder or other suitable means. Said tube *g* is enough larger in diameter than tube *a* to form an annular recess between the same for the purpose of leading steam or air, forced through apertures *e*, into the air, as hereafter described.

The instrument is caused to give synchronous vibrations to the air in this wise: When steam or air is forced into tube *a* at *b*, it meets an obstruction in partition *d*, which causes the current to flow through apertures *e* into the annular recess intervening the tubes, from which it flows in a stream (of shape of annular recess at *i*) over apertures *f*, causing rapid vibrations in the air, by reason of the friction at the point of exposition *f* of air contained in tube *a*. Said friction produces synchronous vibrations in the air more or less long, in proportion to capacity of tube *a*, size of apertures *f*, and swiftness of the passing current, their proper combinations producing high or low notes at will, forming a cheap and efficient whistle, not affected by slight alteration; as, for instance, diameter of tubes, size and number of apertures, which can be altered without any other result than alteration in the tone.

Claim.

What I claim, and desire to secure by Letters Patent, is—

The combination of tubes *a* and *g*, as set forth in combination with the apertures *f*, for the purpose specified.

THOMAS SHAW. [L.S.]
